DESIGN FOR A WATCH BAND OR ARTICLE OF SIMILAR NATURE

William Diehl, Summit, N. J., assignor to Jacques
Kreisler Manufacturing Corporation, North
Bergen, N. J., a corporation of New Jersey

Application May 8, 1944, Serial No. 113,514

Term of patent 7 years

(Cl. D45—4)

To all whom it may concern:

Be it known that I, William Diehl, a citizen of the United States, residing at Summit, county of Union, and State of New Jersey, have invented a new, original, and ornamental Design for a Watch Band or Article of Similar Nature, of which the following is a specification, reference being had to the accompanying drawing, forming a part thereof.

Fig. 1 is a perspective view of a watch band showing my new design with the links in extended position;

Fig. 2 is a fragmentary top plan view thereof showing the links in closed position;

Fig. 3 is an edge view of Fig. 2;

Fig. 4 is a side view thereof.

The portions shown in dotted lines are a repetition of the portions disclosed in full lines.

I claim:

The ornamental design for a watch band or article of similar nature, as shown and described.

WILLIAM DIEHL.
